US00D743009S

(12) **United States Design Patent**
Young et al.

(10) **Patent No.:** US D743,009 S
(45) **Date of Patent:** ** *Nov. 10, 2015

(54) **GASKET HAVING RAISED SEALING SURFACE PATTERN**

(71) Applicant: **Garlock Sealing Technologies, LLC**,
Palmyra, NY (US)

(72) Inventors: **Joseph D. Young**, Palmyra, NY (US);
Stefan Pitolaj, Palmyra, NY (US);
Aydin Aykanat, Palmyra, NY (US);
Earl J. Rogalski, Palmyra, NY (US)

(73) Assignee: **Garlock Sealing Technologies, LLC**,
Palmyra, NY (US)

(*) Notice: This patent is subject to a terminal disclaimer.

(**) Term: **14 Years**

(21) Appl. No.: **29/502,406**

(22) Filed: **Sep. 16, 2014**

(57) **CLAIM**

The ornamental design for a gasket having raised sealing surface pattern, as shown and described.

DESCRIPTION

FIG. 1 is a front perspective view of the gasket;

FIG. 2 is a top plan view of the gasket, which is identical to a bottom plan view of the gasket;

FIG. 3 is a front side elevation view of the gasket, which is identical to a rear side elevation view of the gasket; and,
FIG. 4 is a right side elevation view of the gasket, which is identical to a left side elevation view of the gasket.

1 Claim, 3 Drawing Sheets
